UNITED STATES PATENT OFFICE.

ARTHUR D. JONES, OF DES MOINES, IOWA.

METAL POST.

Application filed December 9, 1922. Serial No. 605,971.

To all whom it may concern:

Be it known that I, ARTHUR D. JONES, a citizen of the United States, and a resident of Des Moines, in the county of Polk and 5 State of Iowa, have invented a certain new and useful Metal Post, of which the following is a specification.

My invention relates to metal posts, preferably of galvanized steel.

10 The object of my invention is to provide a post, made of iron or steel, properly galvanized to prevent corrosion, and so constructed that the post can be readily formed to shape without destroying the galvanizing coat.

A further object is to provide a post made from a single sheet of metal formed into a hollow cylindrical tube, so as to have maximum strength with a minimum weight 20 of material, with the edges of the sheet in-turned, to leave no projections, secured together to make the post rigid and provided with simple staple receiving means.

Still another object is to provide a post 25 of the kind mentioned having means for receiving ordinary standard staples at practically any height on the post, so arranged that the staples may be driven in in the usual way and will in the process of driving 30 be bent to holding position, without leaving any exposed points capable of causing injury.

An additional object is to provide such 35 a post having staple receiving means so arranged that the staples may be readily and easily removed without injury to the post, so that the wire on the post may be easily removed or replaced.

With these and other objects in view, my 40 invention consists in the construction, arrangement and combination of the various parts of my device, whereby the objects contemplated are attained, as hereinafter more fully set forth, pointed out in my claim, and 45 illustrated in the accompanying drawings, in which:

Figure 1 shows a front elevation of a post embodying my invention.

Figure 2 shows a side elevation of the 50 same with the wire installed thereon shown in section.

Figure 3 shows an enlarged, detail, vertical sectional view taken on the line 3—3 of Figure 1.

Figure 4 shows a plan view of the sheet 55 of metal from which the post is made, part being broken away.

Figure 5 shows a top view of the post.

Figure 6 shows a horizontal, sectional view 60 taken on the line 6—6 of Figure 2.

Figure 7 shows a detail, vertical, sectional view taken on the line 7—7 of Figure 2.

Figure 8 shows an inside elevation of a portion of the post taken on the line 8—8 65 of Figure 5; and

Figure 9 shows a perspective view of a portion of the partly finished post just before the edges are fastened together.

My improved post is made from a sheet 70 of metal, such as is shown in Figure 4, the sheet being rolled to form a hollow cylindrical body, indicated in the drawings by the reference character 10. The sheet which I have indicated as A, is bent along its side edges as at 11, along vertical lines equi-distantly spaced from the opposite side edges to form portions 12 which project inwardly from the body of the post adjacent to and parallel to each other, as shown in Figure 5.

80 The post is shown in partly formed position in Figure 9.

The members 12 are secured tightly together by electric welding, rivets or other suitable means. They form the means for 85 connecting the edges of the post to leave a post which is smooth on the outside. They also afford a longitudinal reinforcing rib. Furthermore the members afford staple receiving and holding means.

90 When the sheet is in the blank, the portions 12 have grooves 13 stamped or otherwise formed in them, as shown in Figure 4. These grooves are arranged to be opposite each other in the finished post to thus 95 form staple receiving passages. In each portion or member 12, the grooves 13 are arranged in pairs with their outer ends practically communicating as shown in Figure 8.

100 From their outer ends, the grooves 13 of each pair are curved away from each other on the arcs of uniform circles of substantial diameter. The grooves 13 are so arranged that when the post is formed it has, along its vertical joint, a series of equi-distantly vertically spaced holes or passages, arranged at a distance apart corresponding

to the distance between the arms or prongs of a standard fence staple 14.

The staple can then be started into any two adjacent holes and driven in. The 5 staples will be bent on the arcs of circles either as shown at B or as shown at C in Figure 3, depending on what holes are used. The horizontal wire 15 of the fence will be held by the staple in the usual way.

10 The arrangement of the holes or passages formed by the grooves 13 is such that the wire 15 can be easily secured at any height on the post.

When it is desired to remove the wire 15 and the staples a sharp pair of nippers is used to cut the staple in two just at its middle point, and on account of the curvature of the staple receiving passage on the arcs of circles, the half staples can be easily 20 pulled out in view of the fact that their curvature is on the same arc of a circle as the passageway. My post is very practical in view of the fact that the wire fence can be as easily changed on it as on the ordinary 25 wooden posts.

It is obvious that even if the staples project inwardly from the members 12, they can cause no harm to men or animals.

The post may be made of galvanized steel, 30 and its construction is such that the galvanizing will not readily be injured. Its shape,

that of a hollow cylinder, gives it great strength.

The arrangement of the members 12 is such that they connect the edges of the post rigidly together while permitting the post to retain its cylindrical form without projecting parts. They also form a strong reinforcing rib. This is of special value in preventing the bending of or serious injury to 40 the top of the post when it is being driven into the ground, since the strong rib-like members 12 take a large part of the impact of the driving blows. These members 12 also provide means for the staple receiving 45 passages.

Wire can be put on these posts or removed therefrom easily and readily, as often as may be desired without injury to the post.

I claim as my invention:

A metal post comprising a sheet formed into a hollow cylinder with inwardly projecting adjacent parallel strips at its edges, secured together and forming a longitudinal, internal rib, said strips having a series of 55 corresponding adjacent grooves forming staple receiving passages curved on the arcs of circles alternately toward and from each other.

Des Moines, Iowa, October 11, 1922.

ARTHUR D. JONES.
